Fig. 3

The characteristic features of my design reside in the specific configuration of the receptacle hood in combination with a trash container, as best illustrated in FIGS. 1 and 2 on the drawings.

I claim:

The ornamental design for a trash receptacle, as shown and described.
